DOLL

Helen G. Cooke, Aurora, Colo.

Application November 17, 1952, Serial No. 22,326

Term of patent 14 years

(Cl. D34—2)

To all whom it may concern:

Be it known that I, Helen G. Cooke, a citizen of the United States, residing at Aurora, State of Colorado, have invented a new, original, and ornamental Design for a Doll, of which the following is a specification, reference being had to the accompanying drawing, forming a part thereof.

Fig. 1 is a front elevation of a doll, embodying my new design;

Fig. 2 is a side elevation of the doll of Fig. 1; and

Fig. 3 is a bottom view of the doll of Fig. 1.

I claim:

The ornamental design for a doll, as shown.
HELEN G. COOKE.
